(57) **CLAIM**

The ornamental design for a wall sconce lighting fixture, as shown and described.

DESCRIPTION

FIG. 1 is a perspective view from above of the wall sconce lighting fixture in accordance with my design, illustrated in an environment of a lamp;

FIG. 2 is a perspective view from below of the wall sconce lighting fixture in accordance with my design;

FIG. 3 is a top view of the wall sconce lighting fixture in accordance with my design;

FIG. 4 is a bottom plan view of the wall sconce lighting fixture in accordance with my design;

FIG. 5 is a left side elevational view of the wall sconce lighting fixture in accordance with my design;

FIG. 6 is a right side elevational view of the wall sconce lighting fixture in accordance with my design; and,

FIG. 7 is a front elevational view of the wall sconce lighting fixture in accordance with my design.

The backplate, bow bache and pentalogs include a faux ancient stone finish new prompt. The rear elevation is unornamented and follows the contour shown in FIGS. 5 and 6.
